(57) **CLAIM**

The ornamental design for a display screen or portion thereof with an animated graphical user interface depicted in a sequence, as shown and described.

DESCRIPTION

FIG. 1 is a front view of a first image in a sequence of a display screen or portion thereof with an animated occluded vehicle icon;

FIG. 2 is a front view of a second image thereof; and, FIG. 3 is a front view of a third image thereof.

The broken lines shown in FIGS. 1-3 illustrate the display screen or portion thereof and form no part of the claimed design.

The appearance of the animated graphical user interface transitions sequentially between the images shown in FIGS. 1-3. The process or period in which one image transitions to another forms no part of the claimed design.
